UNITED STATES PATENT OFFICE.

WILHELM B. BRONANDER, OF MONTCLAIR, NEW JERSEY, ASSIGNOR TO AMERICAN MACHINE & FOUNDRY COMPANY, A CORPORATION OF NEW JERSEY.

CIGARETTE-PACKAGING MACHINE.

Application filed October 17, 1925. Serial No. 63,008.

This invention relates to an improved cigarette packaging machine which is particularly designed, adapted, and used, as complementary to, and for packing the product of, the new standard duplex cigarette machines of the industry, although it will of course pack cigarettes made on other machines. The standard duplex cigarette machines of the industry have capacities of sixteen hundred cigarettes per minute, by far the greatest output known. To take care of this great manufacturing output, the present machine is designed, adapted, and used, for packaging sixteen hundred cigarettes per minute, in eighty packages, each containing twenty cigarettes. This is by far the greatest packaging output known. By the use of such machines, in place of those of less than one-half of their capacity which were heretofore of necessity employed, the capacity of cigarette factories is greatly increased, without additional investment in enlarged or new buildings; the overhead expenses of existing factories are decreased; the number of requisite machines, machine operators, inspectors, and mechanics, is decreased; better cigarettes, because less handled, are produced; and said cigarettes are produced at decreased cost. The main object of the present invention is, therefore, the production of a cigarette packaging machine of this high capacity, and aiding in effecting these desirable results. But the productive speed is so high that the old way of compacting the cigarettes, in order to prepare them for wrapping, is unsuitable; the old way of wrapping the compacted cigarettes, is unsuitable; and the old way of sealing the wrapped cigarettes, or drying the paste employed on the wrappers, is unsuitable. Further objects of the invention, therefore, are the production of means for compacting the groups or collocations of cigarettes progressively, step by step, with brief pauses in the compacting action between steps in order to give the tobacco time to adjust itself to its closer quarters without losing its life or resiliency; the production of improved means for wrapping the collocations of cigarettes; and the production of improved means for sealing the packages or drying the paste employed. With these and other objects not specifically mentioned in view, the invention consists in certain constructions and combinations which will be hereinafter fully described

and then specifically set forth in the claims hereunto appended.

In the accompanying drawings, which form a part of this specification and in which like characters of reference indicate the same or like parts, Fig. 1 is a plan view of a machine constructed in accordance with the invention, and showing the arrangement of the several units; Fig. 2 is a plan view of the actuating parts, below the bed plate; Fig. 3 is a front elevation of the cigarette hopper which supports a mass of cigarettes to be operated upon; Fig. 4 is a front elevation of the compacting means; Fig. 5 is a sectional side elevation of the compacting means; Fig. 6 is a detail of the compactor gear adjuster; Fig. 7 is a side elevation of the label feed, label wrapper, and stacker; Fig. 7^a is a side elevation of the tinfoil feeding and wrapping devices; and it also shows the hopper, compactor and actuating parts; Fig. 8 is a detail view of the tinfoil feed roller disengaging device. It may be here noted that sheets 5 and 6, when joined together along the lines I—I of Figs. 7 and 7^a, form a complete side elevation of the machine viewed from the folder side, on the left in Fig. 1. Fig. 9 is a side elevation of the tinfoil feed, etc., as in Fig. 7^a, but viewed from the other side of the machine; Fig. 9^a is a side elevation of the label feed as in Fig. 7, but viewed from the other side of the machine. Sheets 7 and 8, when joined together along the lines II—II of Figs. 9 and 9^a, form a complete side elevation of the machine viewed from the right hand side in Fig. 1. Fig. 10 is a front elevation of the tinfoil feed; Figs. 11 and 12 show the details of the tinfoil stop-plate; Fig. 13 is a front elevation of the label feed; Fig. 13^a is a detail of a suction nipple; Fig. 14 is a rear elevation of the stacker; Fig. 15 is a diagrammatic plan view of the tinfoil and label folders, showing the progress of the package; Fig. 16 is a diagrammatic elevation of Fig. 15, with the label folder shown in section; Fig. 17 is a rear view of the indexing device; Fig. 18 is a side view of the same showing actuating parts; Figs. 19 to 27 illustrate the successive stages of wrapping; and Fig. 28 shows the actuating crank and the movement of the tinfoil feed rocker arms.

In carrying the invention into effect, there is provided means for separating loose col-

locations of cigarettes from a mass in a hopper or other suitable receptacle, means for progressively compacting said collocations, step by step, to gradually, though quickly, 5 work them into their proper condition for wrapping, but without loss of tobacco life or resiliency; and, further, means are provided for rapidly wrapping the compacted collocations. In the best constructions 10 contemplated, the wrapping means includes improved means for applying an inner wrapper of tinfoil and an outer label or wrapper of paper to each collocation of cigarettes, and improved means for stacking or holding the 15 wrapped collocations until the adhesive employed has had time to dry. These various means and parts may be widely varied in construction within the scope of the claims, for the particular machine selected to illustrate 20 the invention is but one of many possible concrete embodiments of the same. The invention, therefore, is not to be restricted to the specific construction shown and described.

25 Referring to the drawings: The cigarettes to be packed are placed in a suitable receptacle on the machine by an attendant who replenishes the supply from time to time. The packing capacity of the present machine being equal to the manufacturing capacity of the standard duplex cigarette machine in connection with which it is designed to be used, the cigarettes to be packed may be inspected and transferred directly from the 30 cigarette making machine to the present cigarette packing machine, thus effecting a saving in storage space, eliminating unessential handling, and resulting in packaging before the tobacco in the cigarettes dries out 35 and becomes brittle. Such a receptacle is the hopper marked 30. This hopper is provided with hinged agitator plates 31 of well known construction and operation. The bottom of the hopper opens into two downwardly diverging ducts 32. A removable and transparent plate 33 rests against the otherwise open front of the hopper 30. This plate serves to keep the cigarettes in proper position in the hopper and to permit ready inspection of their progress. By removing the plate 33, all of the cigarettes in the hopper 40 become at once accessible, so that a defective cigarette may be removed, or an accidentally misplaced cigarette may be straightened out.

45 The agitator plates 31 (Fig. 3) are connected by arms 34, rod 35, bellcrank 36, and pushrod 37, to the lever 38. This lever is pivoted on a shaft 39, and it carries a cam bowl 40 engaging an open cam 41 on a cam 46 shaft 42, the latter being driven from the shaft 215 by the gears 216 and 218 (Fig. 2). A coil spring 43 (Fig. 3), which is interposed between the bed plate 47 and a collar 44 on the pushrod 37 keeps the cam bowl 40 55 in contact with its cam. The agitator plates

31 can be stopped while the machine is running, if desired, by forcing the pushrod 37 down and slipping the hinged latch 45 over a pin 46 on the collar 44, which results in throwing the cam bowl 40 out of engagement 70 with its cam 41.

As the cigarettes are shaken down into the diverging ducts 32 they become, in each duct, arranged in three rows with staggered centres, by means of the partitions 364 and 75 stop 365, the centre stops being one-half the thickness of a cigarette higher than the end stops.

80 Loose collocations of cigarettes are alternately separated from the mass in the hopper 30 and ducts 32, and alternately delivered to compacting means. In the specific machine shown and described, each collocation contains twenty cigarettes. The separation of the collocations from the mass is 85 effected as follows: Enough cigarettes for one collocation and one package are pushed out from each of the ducts 32 by plates 49 (Fig. 1) carried by a plunger 50, these plates being made of a height to engage seven cigarettes in the end rows and six cigarettes in the middle row of each duct 32. There are of course two of these plungers, and they come into operation alternately, so that although the productive speed of the machine 90 is high, the operating speed of each plunger mechanism is relatively low; and excessive wear and tear is avoided. The plungers 50 run on guide rods 51 which are fastened to clamp brackets 52 and 53 bolted to the bed 100 plate 47. The plungers are actuated by levers 54 (Fig. 7^a) pivoted on the shaft 55, and connected to them by the rods 94. The levers 54 carry cam bowls 170 tracking on cams 56 on the shaft 57. The cam bowls are 105 held to their duty by long springs 58 connecting the levers 54 with the rear frame 48 (Fig. 2). The shaft 57 is driven from the main shaft 215 by means of the gears 217 and 219. While the machine is running, either one, or both, of the plungers can be 110 stopped by hooking the latch 59 (Fig. 7^a), pivoted to the side of the hopper frame, over the pin 60 of the plunger 50. The latches 59 are fastened to the hopper frame 111 by 115 springs 112 which are so positioned with relation to the pivots 171 that the latches are locked in place at both of their extreme positions.

120 The plates 49 force the collocations of cigarettes from the ducts 32 directly into the range of action of the compacting means which prepares them to be wrapped. This compacting means includes an outer rotor 62 (Figs. 4 and 5), an inner rotor 63, and the 125 cam 64. The outer rotor, with its hub 65, rotates around an eccentric 66, forming an integral part of a stationary shaft 67, and has the arms 68 provided with the top plates 69. It is secured in position by the end plate 130

78 which is held to the end of the eccentric 66 by the screw 79. The inner rotor 63, with its hub 70, rotates around the shaft 67 which is supported by the pedestal 92 (Figs. 5 1 and 7^a). The cam 64, between the outer and inner rotors, rotates around the eccentric 73 which is also integral with the stationary shaft 67. The arms 72 of the inner rotor have bosses 74 in which slide rods 75 fitted with the plates 76. Coil springs 77, attached to the plate 76 and to the arms of the inner and outer rotor, keep the sliding rods 75 in engagement with the cam 64.

The driving gear 80 of the outer rotor 15 has bosses 82 abutting the hub arms 83 of the outer rotor 62 and secured thereto by the bolts 84. These bosses 82 pass through the openings 85 of the cam 64 which provide enough clearance to permit a limited but 20 free reciprocating motion. The gear 81 of equal diameter and pitch as the gear 80, mounted rotatably on the hub 70 of the rotor 63, has screws 86 (Fig. 6) bearing against the lug 87 of the hub 70. By slackening one screw and tightening the other, the angular relation of the walls of the compactor can be regulated. Both gears 80 and 81 mesh with a pinion 88 keyed to the shaft 89 which is supported in bearings 90 and 91 of the pedestals 92 and 93 respectively (Fig. 30 1). It will now be understood that the compacting means includes a series of expanding and contracting collocation pockets having movable walls.

The amount of eccentricity of the eccentrics 66 and 73 is governed by the required size of the finished package in relation to the number and diameter of the cigarettes prior to compacting. When the rotors and cam 40 revolve around the stationary shaft 67 and its eccentrics, there is produced a relative reciprocating motion of the rotor 62 and cam 64 as they rotate on different centers. The eccentric 66 regulates the amount of expansion and contraction, between the walls of the rotors, which determines the ultimate thickness of the package. The eccentric 73 regulates the amount of expansion and contraction, between plates 69 and 76, which 50 determines the ultimate width of the package. The component parts of the compactor are so arranged that maximum expansion prevails in the pockets at which the collocations of cigarettes enter from the hopper, and the collocations are ejected from the compactor after maximum contraction has 55 taken place and after the pocket walls have again opened part of the way to relieve all pressure on the collocation at the moment of ejection.

The compactor rotates in the direction of the arrow shown at the left in Fig. 4, its motion being made intermittent by the aid of the indexing device to be hereinafter described, and the expansion is maximum at

95 and the contraction is maximum at 96. The collocations of cigarettes are introduced at 97, on either side of 95, and are expelled at 98, half way between 96 and 95.

The cigarettes entering the compactor at 97 are stopped by plates 344 mounted on blocks 345 which are pivoted on pins 346 of brackets 347. These brackets 347 are fastened to the bed plate of the machine, and they have pivoted latches 348, with set screws 75 349, for keeping the plates 344 in position. By lifting the latches, the plates 344 can be swung out and away from the compactor to facilitate the cleaning of the compactor pockets.

The step by step movement given to the compactor, and the progressive compacting action developed by the rotors and cam during each such movement, results in gradually, though quickly, reducing each collocation 85 of cigarettes to its proper condition for being wrapped, without destroying the natural resiliency or life of the tobacco. Compacting to the required degree in one movement, in the extremely limited time available, 90 would have this undesirable effect, particularly upon freshly made cigarettes.

As soon as a collocation of cigarettes is thus made ready for wrapping, it is pushed out of the compactor pocket at 98 into mechanism for wrapping it in tinfoil, by a plunger 99 (Figs. 1 and 7^a) which is mounted on a slide 175 sliding on a guide bar 100, the latter being fastened to the side of the hopper frame 111. The plunger 99 and slide 175 have a link connection 172 with a lever 173 which is pivoted on a shaft 174 and connected by a rod 101 with a bellcrank 102 (Fig. 7), the latter being pivoted on the fulcrum shaft 103 and engaging a closed cam 104 (Fig. 2) on the cam shaft 42, through the agency of its cam bowl 268.

The compactor and other parts of the machine have intermittent motion obtained by an indexing device on the shaft 89 (Figs. 17 and 18), and including the disc 105 which is provided with equally spaced studs 106. On the shaft 89, adjacent the disc 105 but separated therefrom by the boss 107, is an arm 108 carrying pawls 109 and 110 pivoted on pins 129. The arm 108 is actuated by an eccentric 113 on the cam shaft 42, through the agency of a lever 125 and rod 128. The pawls 109 and 110 grip the stud 106^a between them. The pawl 109, which, on the downward stroke of the lever, is kept pressing against the stud by the spring 126, is, at the end of the stroke, turned away from the stud by the shoulder 114 of the stop pin 127 which at the same time engages the notch 115 of the disc 105, being pushed up by the spring 116 in the stop pin guide 117, the latter being fastened to the bed plate 47. The pawl 110, in resilient tangential contact with the stud, is disengaged on the upward 130

stroke of the lever 108, by the action of the spring 118. The lever moves upward until the pawls engage with the next following stud, the pawl 109 pressing down on the spring and the pawl 110 yielding on coming into contact with the stud but being kept in resilient relation therewith by the action of the spring 118. At the moment the downward stroke begins, the stop pin 127 is withdrawn from the notch 115 by the lever 119, then engaging lugs 120 of the stop pin, and connected by a rod 121 with the lever 122 which is pivoted on the shaft 39, and has a cam bowl 123 engaging an open cam 124 on the shaft 42.

The tinfoil which forms the inner wrapper of the packages is from time to time placed on the reels 130 and 131 (Figs. 1, 9 and 10), the hubs 132 and 133 of which are inserted into the sleeve of the revoluble support 134, and held in place by the catch levers 135, in conjunction with springs 136, engaging with grooves 137 on the reel hubs. The reel 130 is normally in action, while the reel 131 is a loaded spare reel, always readily available for use in the event of defective tinfoil, or an exhausted supply on the reel 130. The support 134 rests on the top of a support 138 which is bolted to the pedestal 92. A lock opening lever 139, on the support 138, which engages the notches 140 of the support 134, permits the support 134 to be swung around 180°, thus bringing the spare reel 131 into the position of the reel 130. A fresh reel 131 can thus be almost instantly substituted for an empty reel 130, which can then be taken off and replaced by a loaded one while the machine is running. The tinfoil is drawn from the reel 130, over the smoothing wedge 141, by rollers 142 and 132 around which are looped the guide strips 350 and 351 which fit grooves 352 and 353 respectively, and serve as guides for the tinfoil, introducing it into the upper guides 145 which are supported by the bracket 146 from the pedestal 92. The guides 145 are provided with spring strips 144 which guide the tinfoil past the knife gap into the lower guide 155.

The tinfoil is cut to size by the knife 147 which is resiliently pivoted on the bracket 146 by means of the pin 148 and spring 149. A link 150 connects the knife with a crank 151 which is pivoted on the shaft 152, and has a cam bowl 153 engaging a vertical cam 154 mounted on the shaft 187, thereby causing the knife to oscillate in a horizontal plane, the tinfoil being cut on the backward stroke of the knife. The tinfoil, cut to size, subsequently passes through the lower guide box 155 until stopped by the plate 165 (Figs. 11 and 12) on the sleeve 166 which has a lug 167 and is revolvably mounted on a pin 168. This pin has a hand knob 169, and is turnable in the bracket 354 until stopped in

either direction by either of two flat sides of the cam 355 abutting against the ledge 356 of the bracket 354. Fixedly mounted on the pin 168 is a sleeve 358 having a lug 359 which is held in resilient relation to the lug 167 by the spring 360. The relative position of the lugs can be adjusted by means of the screw 361 which is threaded through the lug 359 and abuts the lug 167. This allows the stop plate 165 to be raised or lowered when 75 in position. The coiled spring 362, on the pin 168, keeps the cam 355 pressed against the bracket 354, the friction preventing the stop plate from being jarred out of position when in its working position. By turning 80 the knob 169, the stop plate can be swung away from the guide box, allowing the removal of any tinfoil in the guide box after the machine is stopped.

In order to keep the tinfoil stationary 85 while it is being cut, thus insuring a straight cut, a counter travel of the tinfoil, which is equal to the feeding speed, is periodically obtained by raising the feed roller arm 161, pivoted on the shaft 156 which has a bearing 90 in the pedestal 92, by means of a crankpin 157 (Fig. 28) of the crank 158 on the shaft 159, engaging the guide slot 160 of the arm 161. This imparts an up and down motion to the feed rollers, alternately stopping and 95 accelerating the speed of the tinfoil. To facilitate insertion of the tinfoil between the feed rollers, the roller 143 is made to be moved outward, by a lever 164 actuating the eccentric 162 against the adjustable spring 100 163 which, on releasing the lever, brings the roller back to its normal position.

Each collocation of cigarettes from the compactor pocket 98 is pushed by the plunger 99 (Figs. 15 and 16) in between the 105 belts 176 and 177 and the horizontal rollers 178, the tinfoil having been folded lengthwise over the collocation, as shown in Fig. 19, by the forward movement of the plunger, the roller 178 effecting the forward tucks 110 (Fig. 20). The folding plates 180 effect the preliminary upward folding of the lower side flaps (Fig. 21), these folds being accentuated by the pressure of inclined rollers 181 rotating in the direction of their 115 respective arrows. The folders 182 and 183 effect the downward folding of the upper side flaps (Fig. 22), these folds being accentuated by the inclined rollers 184 rotating in the same direction as the rollers 181, but their action is downward and forward by reason of their more elevated position and inclination opposite to that of the rollers 181, which act upward and forward. These rollers overcome the tendency of the tinfoil 120 to drag on the folders and become displaced on the collocation of cigarettes during the rapid movement of the tinfoil over the folders; and in so doing, they accentuate the folding action, causing the folded tinfoil 125 130

to lie smoothly and flatly against the collocation of cigarettes.

The belt 177 runs over its actuating drum 193 on the shaft 194 (Fig. 7^a), over the idler 195 on the bracket 196 rotatably mounted on the shaft 194, then over the guide roller 197, and thence over the top of the lower supporting bracket 200 to the roller 198 and back to the drum 193. The belts 176 and 177 are held taut by the idle rollers through the pulling action of the springs 199. The bracket 191 has a hinged extension 191^a which can be swung up by operating the toggle 179 (Fig. 7), to facilitate the removal of a package in the event of torn tinfoil or other trouble.

The tinfoil feed and folding mechanism is driven as follows: The sprocket 201, on the cam shaft 42, drives the sprocket 202 on the belt drum shaft 194. The sprocket 203, on the same shaft, drives the endless chain 204, which runs over the idler 205, thence over the sprocket 206 on the belt drum shaft 187 and sprocket 207 on the shaft 156, thence over the sprocket 208 on the shaft 209, which shaft has bevel gears 210 driving the bevel pinions 185 of the inclined rollers 181 and 184. The shaft 156, of the tinfoil feed, carries a sprocket 211 which drives the feed roller 142 through the sprocket 212 and spur gears 303. On the shaft 156 is also keyed a spur gear 213 meshing with a gear 214 on the shaft 159, the latter having a crank 158 which actuates the arm 161 by means of a crankpin 157 engaging a block 363 slidable in the guide slot 160.

After the tinfoil or inner wrapper has been applied to a collocation of cigarettes, the collocation passes directly into the label or outer wrapper applying mechanism which puts the outside wrapper or label around the tinfoil wrapper, the labels already cut to size, being fed from a magazine 270, into which a supply is stacked from time to time, into the path of the package as it leaves the tinfoil folder and enters the label folder. The tinfoil-wrapped package is propelled from between the belts 176 and 177 into the label folder by the prongs 221 which swing on pivots 222 on the pieces 223, the latter being slidable on a guide bar 224. These prongs have cam bowls 225 engaging stationary cams 226 which operate to swing the prongs from the dotted-line outward position to the full-line inward position (Fig. 15) when the slides 223 are moved forward. The slides 223 are actuated by the levers 227 pivoted on the shaft 228 by a common hub 229 provided with an arm 230 connected by the rod 231 with a lever 232 pivoted on a bellcrank 233. The lever 232 is oscillated by a rod 234 connected with a lever 235 fulcrumed on the shaft 103 and having a cam bowl 236 engaging a closed cam 237 on the

cam shaft 42. At the beginning of the return stroke, the prongs, which are provided with a slot 238, swing inward, and, reaching over the guide 239, engage the package and impart the rear tuck to the tinfoil wrapper (Fig. 23). As the package enters the label folder the label folds itself over it lengthwise (Fig. 24), the fold being insured by the roller 240 in the cover plate 241, and immediately receives the forward tuck through the agency of the tuckers 242. The package is further propelled over the bottom bars 243 by the rack 244 which has an upright pusher plate 245. The rack is retracted downwardly by rods 246, pivoted on the lever 247, which, through the agency of the gears 248 and 249, turns in unison with, but in opposite relation to, the bellcrank 233, the latter being actuated by a rod 250 which is connected with a lever 251 fulcrumed on the shaft 103 and having a cam-bowl 252 engaging the closed cam 253. The extreme positions of the rack are indicated by the dotted lines in Figs. 15 and 16.

The rack propels the package past folders 254 which fold the lower side flaps upwardly (Fig. 25), the upper side flaps still projecting and passing subsequently over paste wheels 255 under the spring guides 256 of the paster 257. In passing the folders 258, which are fastened to the cover plate 241, the upper side flaps of the label are folded downwardly with their gummed edges pressed over the lower flaps (Fig. 26). The lower rear flap of the tinfoil wrapper has previously been folded up by the rear push plate of the rack.

The package is then propelled onto a plunger plate 259 which is actuated by a rod 260 sliding in a vertical guide 261 and moved up and down by the lever 262 engaging the lever 263, the latter being connected by a rod 264 to a lever 265 fulcrumed on the shaft 103 and actuated by a cam bowl 267 engaging a cam 266 on the shaft 42. The plunger 259 pushes the package upwards into the stacker past the springs 269 which press the package against the lip of the cover plate 241, thus effecting the folding down of the rear flap of the tinfoil wrapper (Fig. 27).

The labels are extracted from the magazine 270 by the suction plate 271 which grips the leading label by suction, and on each of its downward strokes the plate deposits a label between the rollers 272 and 273. The roller 273 is mounted on a rocking bracket 274, and on its upward stroke it meets the suction plate at the end of the downward swing of the latter. The downward travel of the roller 273 guides the label into the guide box 275, through which it passes until stopped by the adjustable prongs 276. The travel of the suction plate is effected by means of a toggle lever 277 on the suction

pipe 278 and connected by a rod 279 with a lever 280, on a sleeve 281, said lever being actuated by a pushrod 282 connected with a lever 283 on the fulcrum shaft 103. The lever 283 has a cam bowl 284 engaging a cam 285 on the cam shaft 42. The ends of the magazine are closed by guide strips 357, the rear guide strips being adjustable.

The travel of the roller 273 is effected by means of levers 286, 287 and 288 on the shaft 289, which shaft passes through the sleeve 281 and is actuated by a pushrod 290 connected to a lever 291 on the fulcrum shaft 103. The lever 291 has a cam bowl 292 engaging a cam 293. The suction valve 294 is controlled by a lever 295, on the shaft 289, actuated through a crank 296 by a pushrod 297 connected with a lever 298 on the fulcrum shaft 103. The lever 298 has a cam bowl 299 engaging the cam 300.

The label feed roller is driven through the sprocket 301 from the sprocket 302 on the shaft 156, the latter being driven by spur gears from the shaft 159.

The pasters are mounted on the rear pedestal 93 of the machine, each paster having a gear 304 mounted on its paste wheel shaft. The gears 304 are driven by gears 305 on a shaft 306 extending across the two pasters below the package runway. One of the gears 305 is in mesh with gears 307 driven by a gear 308 on the shaft 309. This shaft is supported in a bearing 366 and is rotated by a sprocket 310 driven from the shaft 194 by the sprocket 220.

After the label or outer wrapper has been applied to a package, the latter is passed on to a stacker wherein it is held long enough to give the paste time to dry. This stacker includes three endless belts 311, 312 and 313, the belt 311 passing over rollers 314 and 315, the belt 312 over rollers 316 and 317, and the belt 313 over rollers 318 and 319, all rollers being actuated by the chain 320 running over sprockets 321, 322, 323, 324, 325 and 326, causing the belts to run in the direction of the arrows in Fig. 14. The finished package is pushed up between the belts 311 and 312 by the plunger 359 and carried upward in between the resilient discs 327 which grip the packages 343 and carry them around and down in between the belts 312 and 313. They are then conveyed downwards into the chute 328 which is supported by the bracket 329. It will now be understood that these belts form vertical pathways into the bottom of one of which the packages are introduced, and then the discs operate at the top of these pathways to transfer packages to the other pathway. During the circuit, the gummed labels have had time to dry, and the packages are finally deposited on the table 47 of the bed plate, and removed by the operator. The belts are held in non-slipping contact with their

rollers by the adjustable fixed eccentric rollers 330. The shaft 331 of the roller 319 has a sprocket 332 driven by a chain 333 from a sprocket 334 on a shaft 335, which, through bevel gears 336 and 337, the latter being 70 mounted on the shaft 338, is driven by a sprocket 339 and chain 340 from a sprocket 341 on the shaft 308, the latter being driven from the shaft 209 by a chain 310.

The label feed suction plate 271 has bell-shaped suction nipples (Fig. 13^a) of soft rubber or other suitable material, the small end of each nipple being inserted in an aperture 368 of the plate 271 and clamped in place by the grommet 369. This pliable nipple adjusts itself to the varying relative positions of label and suction plate, thereby preventing the label from becoming detached before the operation of transferring the same to the rollers is completed.

In view of the foregoing, a detailed description of the operation of the machine is deemed to be unnecessary, and it is therefore omitted in the interest of brevity.

What is claimed is:

1. A cigarette packing machine, comprising means for separating loose collocations of cigarettes from a mass, means for progressively compacting said collocations step by step, and means for wrapping the compacted collocations.

2. A cigarette packing machine, comprising means for separating loose collocations of cigarettes from a mass, means for progressively compacting said collocations step by step, and means for wrapping the compacted collocations, said separating means including two collocation separating devices delivering collocations alternately to said compacting means.

3. A cigarette packing machine, comprising means for separating loose collocations of cigarettes from a mass, means for progressively compacting said collocations step by step, and means for wrapping the compacted collocations, said separating means having means for arranging collocations of cigarettes in a plurality of rows.

4. A cigarette packing machine, comprising means for separating loose collocations of cigarettes from a mass, means for progressively compacting said collocations step by step and means for wrapping the compacted collocations, said separating means including partitioned ducts and stops therein for arranging collocations of cigarettes in two rows of seven each and one row of six.

5. A cigarette packing machine, comprising means for separating loose collocations of cigarettes from a mass, means for progressively compacting said collocations step by step, and means for wrapping the compacted collocations, said separating means including plungers operative to transfer col-

- locations from the mass of cigarettes directly to said compacting means.
6. A cigarette packing machine, comprising means for separating loose collocations of cigarettes from a mass, means for progressively compacting said collocations step by step, and means for wrapping the compacted collocations, said compacting means including means for forwarding the collocations during the compacting operation. 70
7. A cigarette packing machine, comprising means for separating loose collocations of cigarettes from a mass, means for progressively compacting said collocations step by step, and means for wrapping the compacted collocations, said compacting means including a series of expanding and contracting collocation pockets, and operating connections therefor. 80
8. A cigarette packing machine, comprising means for separating loose collocations of cigarettes from a mass, means for progressively compacting said collocations step by step, and means for wrapping the compacted collocations, said compacting means including a turret provided with expanding and contracting collocation pockets having movable walls, means for intermittently rotating said turret, and means for moving said walls during turret rotation. 85
9. A cigarette packing machine, comprising means for separating loose collocations of cigarettes from a mass, means for progressively compacting said collocations step by step, and means for wrapping the compacted collocations, said compacting means including a turret provided with expanding and contracting collocation pockets having movable walls, an indexing device for intermittently rotating said turret, and eccentric means for moving said walls during turret rotation. 95
10. A cigarette packing machine, comprising means for separating loose collocations of cigarettes from a mass, means for progressively compacting said collocations step by step, and means for wrapping the compacted collocations, said compacting means including a turret consisting of two rotors each carrying a part of the walls of expanding and contracting collocation pockets, and a cam and operating connections and two eccentricities for moving said walls. 100
11. A cigarette packing machine, comprising means for separating loose collocations of cigarettes from a mass, means for progressively compacting said collocations step by step, and means for wrapping the compacted collocations, said compacting means including a turret having expanding and contracting collocation pockets, operating connections therefor, and gearing for intermittently rotating said turret to forward collocations from receiving position to discharging position. 110
12. A cigarette packing machine, comprising means for separating loose collocations of cigarettes from a mass, means for progressively compacting said collocations step by step, and means for wrapping the compacted collocations, said compacting means including a stationary shaft having a section concentric with its axis and also having two eccentricities, a rotor mounted on said concentric section and carrying a part of the walls of a series of expanding and contracting collocation pockets, a second rotor mounted on one of said eccentric sections and carrying the other part of the walls of said pockets, a cam mounted on the other eccentric section of said shaft, and connections whereby rotation of said rotors moves said walls. 120
13. A cigarette packing machine, comprising means for separating loose collocations of cigarettes from a mass, means for progressively compacting said collocations step by step, and means for wrapping the compacted collocations, said wrapping means including forwarding belts, coacting stationary folders, and coacting rollers operating in a direction oblique to the path of said belts. 125
14. A cigarette packing machine, comprising means for separating loose collocations of cigarettes from a mass, means for progressively compacting said collocations step by step, and means for wrapping the compacted collocations, said wrapping means including forwarding belts, coacting stationary folders, coacting rollers operating in a direction oblique to the path of said belts, and means for feeding wrapping material into the range of action of said belts ahead of said folders and rollers. 130
15. A cigarette packing machine, comprising means for separating loose collocations of cigarettes from a mass, means for progressively compacting said collocations step by step, and means for wrapping the compacted collocations, said wrapping means including forwarding belts, coacting stationary folders, coacting rollers operating in a direction oblique to the path of said belts, means for feeding wrapping material into the range of action of said belts ahead of said folders and rollers, and a plunger for pushing collocations of cigarettes from said compacting means into the range of action of said forwarding belts. 135
16. A cigarette packing machine, comprising means for separating loose collocations of cigarettes from a mass, means for progressively compacting said collocations step by step, and means for wrapping the compacted collocations, said wrapping means including means for first enclosing said collocations in a tinfoil wrapper and then in a paper wrapper. 140
17. A cigarette packing machine, com-

prising means for separating loose collocations of cigarettes from a mass, means for progressively compacting said collocations step by step, and means for wrapping the

5 compacted collocations, said wrapping means including means for first enclosing said collocations in a tinfoil wrapper and then in a pasted paper wrapper, and means engaging and holding the doubly enclosed 10 collocations until the paste has time to dry.

18. A cigarette packing machine, comprising means for separating loose collocations of cigarettes from a mass, means for progressively compacting said collocations 15 step by step, and means for wrapping the compacted collocations, said wrapping means including means for applying pasted wrappers to said collocations, and means engaging and holding the sealed packages

20 until the paste has time to dry.

19. A cigarette packing machine, comprising means for separating loose collocations of cigarettes from a mass, means for progressively compacting said collocations 25 step by step, and means for wrapping the compacted collocations, said wrapping means including means for enclosing said collocations in pasted wrappers, and a series of belts engaging, forwarding and holding

30 the sealed packages until the paste has time to dry.

20. A cigarette packing machine, comprising means for separating loose collocations of cigarettes from a mass, means for progressively compacting said collocations 35 step by step, and means for wrapping the compacted collocations, said wrapping means including means for enclosing said collocations in pasted wrappers, and a series of belts and discs engaging, forwarding and holding the sealed packages until the paste has time to dry.

21. A cigarette packing machine, comprising means for separating loose collocations of cigarettes from a mass, means for progressively compacting said collocations 40 step by step, and means for wrapping the compacted collocations, said wrapping means including means for enclosing said

45 collocations in pasted wrappers, a series of belts forming two vertical pathways into the bottom of one of which the packages are introduced, and discs at the top of said pathways for transferring packages to the other pathway.

22. Means for progressively compacting collocations of cigarettes step by step, comprising a series of expanding and contracting 50 collocation pockets having movable walls, and means for intermittently and progressively moving said walls.

23. Means for progressively compacting collocations of cigarettes step by step, comprising a turret provided with expanding 55 and contracting collocation pockets having

movable walls, means for intermittently rotating said turret, and means for moving said walls during turret rotation.

24. Means for progressively compacting collocations of cigarettes step by step, comprising a turret provided with expanding and contracting collocation pockets having movable walls, an indexing device for intermittently rotating said turret, and a cam and operating connections and two eccentrics 75 for moving said walls during turret rotation.

25. Means for progressively compacting collocations of cigarettes step by step, comprising a turret consisting of two rotors each carrying a part of the walls of expanding and contracting collocation pockets, and a cam and operating connections and two eccentrics for moving said walls. 80

26. Means for progressively compacting collocations of cigarettes step by step, comprising a series of expanding and contracting collocation pockets having movable walls, means for intermittently and progressively moving said walls, and gearing for intermittently forwarding said pockets 90 from receiving position to discharging position.

27. Means for progressively compacting collocations of cigarettes step by step, comprising a stationary shaft having a section 95 concentric with its axis and also having two eccentric sections, a rotor mounted on said concentric section and carrying a part of the walls of a series of expanding and contracting collocation pockets, a second rotor mounted on one of said eccentric sections and carrying the other part of the walls of said pockets, a cam mounted on the other eccentric section of said shaft, and connections whereby rotation of said rotors moves 100 said walls.

28. Means for wrapping collocations of cigarettes, comprising forwarding belts, coacting stationary folders, and coacting rollers operating in a direction oblique to 110 the path of said belts.

29. Means for wrapping collocations of cigarettes, comprising forwarding belts, coacting stationary folders, coacting rollers operating in a direction oblique to the path 115 of said belts, and means for feeding wrapping material into the range of action of said belts ahead of said folders and rollers.

30. Means for wrapping collocations of cigarettes comprising forwarding belts, coacting stationary folders, coacting rollers operating in a direction oblique to the path of said belts, means for feeding wrapping material into the range of action of said 120 belts ahead of said folders and rollers, and a plunger for pushing collocations of cigarettes into the range of action of said forwarding belts.

31. Means for wrapping collocations of cigarettes, comprising means for enclosing 125

said collocations in pasted wrappers, a series of belts forming two pathways into one of which said enclosing means delivers the wrapped collocations, and a pair of opposed 5 discs for transferring the wrapped collocations from one pathway to the other.

32. Means for forwarding and holding freshly-pasted wrapped packages until the paste has time to dry, comprising a series of 10 coacting belts forming two pathways into one of which said packages are introduced, and means for transferring said packages to the other pathway.

33. Means for forwarding and holding freshly-pasted wrapped packages until the 15 paste has time to dry, comprising a series of coacting belts forming two vertical pathways into the bottom of one of which said packages are introduced, and a pair of opposed discs at the top of said pathways for 20 transferring said packages to the other pathway.

In testimony wherof, I have signed my name to this specification.

WILHELM B. BRONANDER.
